(57) **CLAIM**

The ornamental design for a strip light, as shown and described.

DESCRIPTION

FIG. 1 is a front elevational view of a strip light showing our new design;

FIG. 2 is a rear elevational view thereof;

FIG. 3 is a left side view, enlarged, thereof;

FIG. 4 is a right side view, enlarged, thereof;

FIG. 5 is a top plan view thereof;

FIG. 6 is a bottom plan view thereof;

FIG. 7 is a perspective view thereof;

FIG. 8 is an enlarged view of portion 8 shown in FIG. 1;

FIG. 9 is an enlarged view of portion 9 shown in FIG. 5;

FIG. 10 is an enlarged view of portion 10 shown in FIG. 5;

FIG. 11 is an enlarged view of portion 11 shown in FIG. 6;

FIG. 12 is an enlarged view of portion 12 shown in FIG. 6;

FIG. 13 is an enlarged view of portion 13 shown in FIG. 7; and,

FIG. 14 is an enlarged view of portion 14 shown in FIG. 7.

The broken lines in the drawings illustrate boundaries and lead lines pertaining to enlarged portions and do not form part of the claimed design.
